CLAIM

The ornamental design for the lime slicer as shown and described.

DESCRIPTION

FIG. 1 is a perspective view of a lime slicer in which all parts, including the illustrated coil, see FIG. 3, are moved together into a compressed position so that only the top and middle sections are visible;

FIG. 2 is a perspective view of the lime slicer in an expanded position in which the top, middle and bottom sections are visible;

FIG. 3 is a perspective exploded view of the lime slicer; FIG. 4 is a side exploded view of the lime slicer;

FIG. 5 is a top view of the lime slicer;

FIG. 6 is a side view of the first side of the lime slicer in an expanded position in which the top, middle and bottom sections are visible;

FIG. 7 is a side view of the second side of the lime slicer in an expanded position in which the top, middle and bottom sections are visible;

FIG. 8 is a bottom view of the lime slicer;

FIG. 9 is perspective view of the lime slicer in which the top and middle sections are visible in an expanded position, and the lower portion of the bottom section is visible in a compressed position;

FIG. 10 is another side view of the first side lime slicer in which the top and middle sections are visible in an expanded position, and the lower portion of the bottom section is visible in a compressed position;

FIG. 11 is another side view of the second side the lime slicer in which the top and middle sections are visible in an expanded position, and the lower portion of the bottom section is visible in a compressed position;

FIG. 12 is a bottom view of the lime slicer separately shown to illustrate its features;

FIG. 13 is a perspective view of a bottom portion of the lime slicer separately shown to illustrate its features;

FIG. 14 is a top view of the bottom portion of the lime slicer separately shown to illustrate its features;

FIG. 15 is a side view of the first side of the bottom portion of the lime slicer separately shown to illustrate its features;

(Continued)

FIG. 16 is a side view of the second side of the bottom portion of the lime slicer separately shown to illustrate its features; and

FIG. 17 is a perspective bottom view of the bottom portion of the lime slicer separately shown to illustrate its features. In the drawings, broken lines represent either portions of the article of manufacture which are not included in the claim or unclaimed environment. The dot dot dash broken lines in FIGS. 3, 13, and 14 depict the boundaries of the claim and form no part thereof.
